UNITED STATES PATENT OFFICE.

JOHN HENRY OSBORNE, OF BLACKHEATH, AND ALFRED WILLIAM BURFORD, OF LEE, LONDON, ENGLAND.

FIRE LADDER AND THE LIKE.

Application filed July 11, 1921. Serial No. 483,873.

To all whom it may concern:

Be it known that we, JOHN HENRY OSBORNE and ALFRED WILLIAM BURFORD, subjects of the King of Great Britain and Ireland, residing, respectively, at Blackheath and Lee, London, England, have invented Improvements in Fire Ladders and the like, of which the following is a specification.

This invention has reference to improvements in motor actuated ladders which are capable of being raised from an approximately horizontal position to a more or less vertical position and lowered, and of being telescopically extended or collapsed. Such ladders are described in the specification of British Letters Patent No. 2502 of 1908 granted to James Compton Merryweather, to which reference may be had for details not herein described and which form no part of the present invention.

An object of the present invention is to enable such ladders to be extended or collapsed whether they are being raised or lowered or are stationary, and raised or lowered whether they are being extended or collapsed or not. A further object is to enable the various motions of the ladder to be effected without reversing the motor driven shaft and without risk of damage to the gears or ladder through the attendant not disengaging the gears from the motor driven shaft at the proper times.

For these purposes the gears between the motor driven shaft and the extending gear and the raising and lowering gear each comprise reversely driven gear wheels to either of which the gear shaft may be connected by a reversing clutch actuated by a hand lever through suitable connections and a means is provided for automatically disconnecting the raising and lowering gear from the motor both when the ladder has been raised to its maximum angle and when it has reached its lowest position, and for disconnecting the extension gear from the motor when the ladder is fully extended.

The accompanying drawings illustrate the raising and lowering and extension gear of a motor driven fire escape ladder of the turntable type embodying the present invention.

Fig. 1 is a side elevation;

Fig. 2 a plan, and

Fig. 3 is a diagram illustrating partly in section, the raising and lowering and ex-

tension gear without the means for disconnecting the gear from the motor driven shaft. *x x* are the screws by which the ladder *y* is raised and lowered about its fulcrum *z* on a turntable platform mounted on an automobile, these features being already well known and constituting no part of the present invention. *q²* is a drum for winding the wire rope *q¹* for extending and collapsing the ladder *y*. *e* is the motor driven vertical shaft the axis of which is coincident with the centre of rotation of the turntable. The motor is not shown but is connected to the shaft *e⁴*.

The shaft *e* is connected by gears *e¹* to the shaft *e²* proceeding from a gear box *e³* and is formed with a worm gear on its upper end which engages with a worm wheel 1 on a spindle 2 carrying two spur wheels 3 and 3^a, (Fig. 3) the wheel 3 of which gears direct with a spur wheel 4 loose on the raising and lowering gear shaft 5 connecting through bevel gears 6 the screws *x*, whilst the other wheel 3^a gears through an idle pinion 3^b with another spur wheel 4^a on the shaft 5; the spur wheels 4 and 4^a gear with similar spur wheels 7 and 7^a loosely mounted on the extension gear shaft 8 geared to the drum *q²*. Between the spur wheels 4 and 4^a and the spur wheels 7 and 7^a are clutched members 4^b and 7^b which are feathered to the shafts 5 and 8 respectively and can be actuated by levers 9 and 10 through levers and link connections.

As will be understood with such an arrangement by suitable manipulation of the clutch levers 9 and 10, each of the shafts 5 and 8 can be driven from an irreversible motor driven shaft in either direction irrespective of whether the other shaft is being driven or the direction in which it is being driven; consequently the ladder can be extended or collapsed during raising and during lowering and whilst held at the desired angle, and can also be raised or lowered about its fulcrum without its length being varied, as may be required. Obviously should the motor driven shaft for any reason be rotated in a direction opposite to that in which it is primarily intended to run, the same results may be obtained by suitably modifying the operation of the clutch levers.

The control lever 9 is fulcrumed at 11 and is coupled by a link 12 to an arm 13 projecting from the spindle 14 of the shifter of

the clutch member on the shaft 5 that is geared to the screws π ; another arm 15 on the spindle 14 is connected by a link 16 to one arm of a bell crank 17, the other arm 5 of which lies in the path of an adjustable stop 18 on the ladder frame and has pivoted to it an adjustable bar 19 projecting into the path of another stop 20 on the ladder frame, the arrangement being such that as 10 the ladder turns about its fulcrum to its lowermost position the stop 18 will actuate the bell crank 17 and throw out the clutch, whilst as the ladder turns about its fulcrum into its highest position, the other stop 20 15 will actuate the bell crank 17 through the bar 19 in the reverse direction and throw out the clutch, the control lever being correspondingly moved in either case even if the attendant be holding it.

20 The control lever 10 is fulcrumed at 21 and is coupled by a link 22 to an arm 23 projecting from the spindle 24 of the fork of the clutch member on the shaft 8 that is geared to the extension wire drum q^2 . The 25 wire rope q^3 , for the purpose of extending the ladder sections, as is usual, is laid on the drum by a pair of guide sheaves 25 carried by a nut 26 mounted on a traversing screw spindle 27 parallel to and driven from the 30 drum q^2 ; the nut 26 is formed with a projection 28 and one arm of a lever 29 fulcrumed at 30 extends into the path of this 35 projection, the other arm of the lever 29 being connected by a link 31 with the arm 23. When the traversing nut 26 reaches a certain 40 position on the screw 27, the rope will have extended the ladder to the full extent and the nut will at the same time actuate the lever 29 and through it the arm 23 in such manner as to throw out the clutch. An automatic stop 45 is not needed to throw out the clutch when the ladder reaches its fully collapsed condition as further rotation of the drum q^2 will simply slack the rope; but such a stop may be provided if desired.

What we claim is:

1. In a fire ladder adapted to be raised and lowered about a horizontal axis and of being telescopically extended or collapsed, a 50 shaft, a pair of spur wheels loosely mounted thereon; a shaft parallel to the first named shaft also having a pair of spur wheels loosely mounted thereon and in constant mesh with the first named pair, a 55 pair of oppositely rotating driving wheels in constant mesh with the spur wheels on one of the said shafts and clutch members

whereby, with all the gear wheels continually in mesh, it is possible to use either shaft 60 by itself or both shafts together with reversal of either or both whenever desired.

2. In a fire ladder adapted to be raised and lowered about a horizontal axis and of being telescopically extended or collapsed, a pair of shafts, a pair of spur wheels, 65 loosely mounted on one shaft, a pair of spur wheels loosely mounted on the other shaft and meshing with the first named pair of wheels, a pair of oppositely rotating driving wheels meshing with the pair of 70 wheels of one shaft, a clutch member adapted to connect either spur wheel of one pair to the companion shaft, a similar clutch member adapted to connect either spur wheel of the second pair to the other shaft, and means 75 for independently operating both clutch members which in neutral position allow both shafts to remain idle whilst all the gear wheels are rotating.

3. The combination with a pivotally mounted fire ladder, and means for raising and lowering the same about its pivot, of a shaft for the operation of such means, a pair of oppositely rotating spur gear wheels loosely mounted on such shaft, a clutching 85 member adapted to temporarily connect each of said wheels alternatively to the shaft, rocking gear adapted to shift the clutch member in opposite directions, a hand operated lever connected to such gear and a lever also connected to such gear adapted to be displaced by the ladder when in its extreme raised and lowered positions.

4. The combination with a pivotally mounted fire ladder and means for extending and collapsing the same embodying a rope winding drum, of a shaft for the operation of such drum, a pair of oppositely rotating spur gear wheels loosely mounted on such shaft, 100 a clutch means adapted to temporarily connect each of said wheels alternatively to the shaft, rocking gear adapted to shift the clutch member in opposite directions, a hand operated lever connected to such gear, a rope guiding sheave arrangement travelling parallel to the axis of the rope winding drum as the latter revolves, and a lever also connected to the clutch operating gear adapted to be displaced by the travelling sheave arrangement when the ladder is fully extended.

Signed at London, this twenty-fourth day of June, 1921.

JOHN HENRY OSBORNE,
ALFRED WILLIAM BURFORD.
